UNITED STATES PATENT OFFICE

ETIENNE SAINTE CLAIRE DEVILLE, OF PARIS, FRANCE, ASSIGNOR TO SOCIETE DES
ETABLISSEMENTS GAUMONT, OF PARIS, FRANCE, A CORPORATION OF FRANCE

FILM-DRAWING DEVICE FOR CINEMATOGRAPHIC APPARATUS

Application filed April 19, 1929, Serial No. 356,583, and in France May 21, 1928.

In the various apparatus such as cameras, film printing apparatus, developing machines, lanterns, and the like, the film is drawn forward by claws or by toothed rollers. 5
6 The said claws or rollers engage in perforations in the film when in contact with the latter, and thus the film is given a continuous or an intermittent motion.

The edges of the film are thus subjected to 10 a considerable stress, these edges being already weakened by the perforations, so that the film is rapidly put out of use after it has been employed for a certain number of times in the screen lantern.

15 The present invention relates to a film-drawing device which has essentially for its object to reduce the stresses and wear of the film, and chiefly during its travel upon the feeding roller and the retaining roller, which 20 parts are found in all cinematographic apparatus, by balancing the tensions at the input and the output ends of said rollers.

The said device essentially comprises a roller which is mounted in an elastic manner, for 25 instance upon a lever oscillating under the action of an adjustable spring, upon which roller the film travels before engaging the toothed driving roller, also employing a second roller upon which the film travels after 30 leaving the toothed roller. This second roller is quite similar to the first in apparatus adapted for continuous travel of the film, but in apparatus employing intermittent travel, the said roller is positively controlled and is 35 combined with a pressing roller which acts upon the edges of the film.

In order to reduce the wear of the perforations, it is preferable to employ at the same time a smooth drum of larger diameter which 40 acts in conjunction with the toothed roller and is loosely rotatable on a shaft parallel to the roller shaft, it being so disposed that the film will be in contact with the said drum upon a certain length of the periphery, while 45 at the same time the film is drawn forward by

the teeth of the driving roller. This complementary device thus assures the engagement of the film perforations with the teeth, and their withdrawal, which operations now take place without the abrupt motion by which the film is torn or broken. 50

The following description with reference to the accompanying drawings which are given by way of example shows the manner in which the said invention may be carried into effect. 55

Figure 1 shows the film-drawing device used in an apparatus adapted for intermittent travel.

Figure 2 shows the corresponding arrangement in an apparatus adapted for continuous travel. 60

Figures 3 and 4 show the combination of a smooth drum with the toothed film-drawing roller.

The cinematographic film supplied by the 65 upper bobbin, which may comprise the special device described in the French patent in applicant's name No. 256,173 dated the 12th of May 1928, entitled: Braking device for cinematographic films, passes over a roller 1 70 mounted on an axle which is secured to the lever 5 oscillating under the action of the spring 7, the film being drawn forward by the toothed drum 2. 75

If the apparatus operates by intermittent action (Figure 1), that is if the part of the film travelling in the film gate and lighted by the illuminant is displaced in an intermittent manner between two free loops, the shaft of the roller 3 which is rotated by mechanical means, is provided with actuating means operating by adjustable friction, and the adhesion of the film is obtained by a pressing roller 4 acting upon the edges of the film. 80 85

The spring 7 and the friction actuating device of the roller 3 are so adjusted that the tension of the film at *ab* will be substantially equal to the tension at *cd*, so that the pressure of the teeth upon the perforations will be 90

moderate and the duration of the film greatly increased.

The same arrangement is applicable to the toothed retaining roller.

- 5 If the apparatus is of the continuous travel type, and is provided with a smooth film-drawing roller whose motion is made regular by a flywheel, as specified in the French Patent No. 600,401 to A. Poulsen and A. C. 10 G. Petersen dated the 7th of July 1925, the tensions *ab* and *cd* can be balanced by mounting the second roller, which freely rotates, upon an axle secured to a lever oscillating by the action of an adjustable spring.
- 15 Figure 2 shows such a device, consisting of a roller 3 which is mounted loose on an axle secured to a lever 6 oscillating under the tension of a spring 8 and so regulated that the tension at *cd* is practically equal to the tension at *ab*.

An improvement which is applicable to both devices above mentioned is shown in Figure 3, and by its use the film is less subject to wear or damage. In this arrangement, there is added to film-drawing roller 2 a drum 9 of the proper diameter, whose circumference is tangent to that of the toothed roller at the middle point of the enveloping arc. The said drum, which has 30 a very light weight, is loose on its axle.

This arrangement has the advantage of mechanically controlling the release of the teeth from the perforations of the film and of preventing the edge of a perforation in contact 35 with a tooth from remaining in contact during a certain rotation of the smooth part of the roller and then suddenly escaping under the effort of traction, which is one of the chief causes of damage.

40 In this manner it becomes possible to drive the film with a single row of teeth cooperating with a single row of perforations, thus leaving free the whole part of the film hitherto occupied by the second row of perforations, and clear to the edge of the film. This arrangement is shown in Figure 4, in which the film has been turned downwards in order to properly show the construction.

As shown in Fig. 4, the guiding member 9 50 preferably consists of two distinct rollers, one engaging the film near the sprocket 2, and the other engaging the film along the unperforated edge thereof. These two rollers are keyed on a common axle.

55 Thus added width 10 may be used for various designs, wording or titles, or in acoustic films for the sound records adapted for reproduction.

It is also possible to eliminate this width 60 if it is not to be used, whereby the cost of the film will be appreciably reduced.

Obviously, the said devices are susceptible of all necessary modifications in detail, without departing from the principle of the invention.

What I claim is:—

1. A film feeding mechanism for motion picture apparatus comprising a toothed film drawing roller adapted to engage the driving perforations of the film, and a smooth 70 guiding roller of larger diameter than said film drawing roller, adjacent to it, and having a tangent plane which is also tangent to the film drawing roller along the same straight line, whereby the film is so guided 75 as to need but a single row of driving perforations.

2. A film feeding mechanism for motion picture apparatus comprising a toothed film drawing roller adapted to engage the driving perforations of the film,—a smooth guiding roller of larger diameter than said film drawing roller, adjacent to it, and having a tangent plane which is also tangent to the film drawing roller along the same straight 80 line, whereby the film is so guided as to need but a single row of driving perforations, and means for equalizing the tensions of the film at the input and at the output ends of said film drawing roller.

3. A film feeding mechanism for motion picture apparatus comprising a toothed film drawing roller adapted to engage the driving perforations of the film, a smooth guiding roller of larger diameter than said film drawing roller, adjacent to it, and having a tangent plane that is also tangent to the film drawing roller along the same straight line, whereby the film is so guided as to need but a single row of driving perforations, two 90 oscillating levers mounted on either side of the film drawing roller, rollers at the ends of said levers for supporting the film and at least two springs adapted to act on said levers respectively for causing the film to be 100 applied against the film drawing roller, whereby the tensions of the film on each side of the film drawing roller are equalized.

4. A film feeding mechanism for motion picture apparatus comprising a toothed film drawing roller adapted to engage the driving perforations of the film, a smooth guiding roller of larger diameter than said film drawing roller, adjacent to it, and having a tangent plane that is also tangent to the film drawing roller along the same straight line, whereby the film is so guided as to need but a single row of driving perforations, an oscillating lever, a roller at the end of said lever, a spring adapted to act on said lever for causing the film to be applied upon the film drawing roller, a driven roller positively connected to the film drawing roller and a roller for applying the film against said driven roller 110 whereby the tensions of the film on either side of the film drawing roller are equalized.

5. A feeding mechanism for films having only one series of driving perforations comprising a film drawing roller, one series of 120

teeth upon said roller adapted to engage the driving perforations of the film, and a smooth guiding roller of larger diameter than said film drawing roller, adjacent to it,
5 and having a tangent plane which is also tangent to the film drawing roller along the same straight line, whereby the film is so guided as to need but a single row of driving perforations.

10 In testimony whereof I have signed this specification.

ETIENNE SAINTE CLAIRE DEVILLE.
